UNITED STATES PATENT OFFICE

JOHN D. PEDERSEN, OF SPRINGFIELD, MASSACHUSETTS

FIREARM

Application filed July 18, 1928, Serial No. 283,537. Renewed March 3, 1931.

This invention relates to improvements in firearms, more particularly guns of the bolt action type, and has to do with an automatic mechanism in such a gun.

5 An object of the invention is to provide an automatic action for a gun having a rotary and reciprocating bolt, with power storing mechanism and firing mechanism containable in a receiver of normal dimensions, viz. substantially the same as of a standard hand operated gun. A further object is to simplify such mechanisms and attain a smooth-running automatic action which will operate efficiently and with certainty under the most

15 severe conditions of use.

The power for the automatic action is obtained from the backward pressure of the fired cartridge against the face of the bolt, the barrel being fixed to the receiver. In utilizing this power, provision is made for initially delaying the opening of the bolt in large part by a force in inertia, whereby the resistance offered by recoil springs or friction is of minor consequence and variation in friction 20 due to lubricated or unlubricated surfaces will not be the controlling element in determining operation or non-operation of the gun.

In order to avoid the use of large masses 30 for inertia which would unduly weight the gun, I have taken advantage of the moment of inertia of a rotary bolt. In the present invention, this is made effective for absorbing a large amount of the firing pressure energy 35 by a high rotative acceleration imparted to the bolt at the initial opening and a long radius of gyration for the bolt obtained by a weight which may be comparatively small and located at the outer end of the bolt handle.

40 The bolt is held to its breech closed position by locking means which act automatically in unlocking the bolt and in combination with the moment of inertia of the bolt prevent a too rapid initial opening of the bolt 45 under the force of the firing pressure. The locking means comprises a helical bearing surface or locking cam in the receiver for action with a locking lug on the bolt, where- 50 by the firing pressure will automatically un-

lock the bolt and give rotation to the bolt for opening.

The efficiency of the helix angle of this bearing surface will determine not only the amount of firing pressure energy dissipated in friction against the locking cam, but also the rotative acceleration imparted to the bolt and the energy absorbed thereby, the friction dissipation varying inversely and the rotative acceleration varying directly with the helix angle efficiency. (Helix angle efficiency is here derived by the same formula as for the efficiency of screw threads.) A helix angle no greater than the angle of repose for the bearing surface will of course have zero efficiency since in that event the bolt lug would lock permanently against the locking cam under any firing pressure. Accordingly, I have adopted for the bearing surface, or locking cam, a helix angle of relatively high efficiency 55 and one considerably larger than the angle of repose for either lubricated or dry surfaces so as to insure that the bolt will open under either condition. A further advantage in the use of a helix angle of high efficiency is that 60 the amount of energy delivered to the bolt for the operation of the breech mechanism 65 will not differ widely between lubricated surfaces and dry surfaces and thus a more uniform action of the mechanism will be obtained 70 under all circumstances.

I have determined experimentally that the angle of repose for such metal surfaces when lubricated is approximately $7^{\circ} 30'$ and for dry surfaces approximately 15° . The preferred helix angle for the locking cam of the present gun is approximately 30° , and this I believe is a radical departure from any hitherto known practice in gun design. The use of a helix angle of such high efficiency is 80 made practical in the present gun by the presence of a large moment of inertia in the bolt and handle, as previously described. The locking cam of the present gun, with a helix angle of 30° , will give an efficiency of approximately 71% when oiled and an efficiency of 85 approximately 46% when dry. Therefore, in a typical example, a design of parts to make available 10 foot pounds of energy to 90 the opening bolt in performing its work of 100

operating the breech mechanism with the surfaces oiled would deliver approximately 6.4 foot pounds to the bolt for the same purpose with the surfaces dry; and this difference of energy in the working bolt would not be too great for practical purposes and consistent performance.

It has been proposed to make an automatic rifle with a helical bearing surface serving as the locking means for a rotary bolt; but in such proposed construction, the bearing surface has a helix angle of very low efficiency so as to dissipate all but a small part of the firing pressure energy in friction. In such construction, the helix angle proposed is only slightly greater than the angle of repose for the bearing surface when well oiled, with the result that if the surface becomes dry or unlubricated it would then permanently lock the bolt against the firing pressure and prevent its automatic opening because of the fact that the angle of repose for the dry surface would be greater than the helix angle employed. In other words, a dry locking cam of such low helix angle efficiency would render the gun non-automatic in its action. A helix angle of low efficiency as described, while useful in the dissipation of energy by friction, has the great disadvantage of requiring that the surfaces be uniformly lubricated at all times, because its efficiency and the working power delivered to the bolt varies greatly with proportionately slight differences in lubrication. In the present invention, on the other hand, a lack of lubrication will make little noticeable difference in the operation of the gun.

A further feature of improvement in the present invention resides in a special construction of the guiding cam which guides the bolt from its rotary movement into its rectilinear movement. This guiding cam is in the receiver facing the locking cam at the opposite side of the bolt lug and has a guiding surface beginning as a helix of approximately the same helix angle as the locking cam and fairing into a translation curve of the more favorable shape for the transition of the bolt into its rectilinear path. The translation curve is carefully designed for an even distribution of friction losses and working energy from the bolt so as to produce a smooth working travel thereof during the opening cycle.

Combined with the foregoing are other improved features in the gun residing in novel and compactly arranged closing means for the bolt, buffer mechanism and firing mechanism, the details and advantages of which will be clearly apparent in the following description taken in connection with the accompanying drawings.

It will be understood that the complete gun comprises a wooden frame or stock and a barrel of suitable construction, but these

parts, not being essential for illustrating the invention, are omitted from the drawings:

Fig. 1 is a side elevation of the receiver of the gun and parts assembled therein, showing in full lines the bolt and bolt handle in breech closed position and in dotted lines the handle, after the bolt has rotated through 90° and moved to the rear;

Fig. 2 is a top plan view of the receiver shown in Fig. 1;

Fig. 3 is a perspective view of the receiver with all its contained parts removed;

Fig. 3a is a diagram illustrating the form of the path taken by the extremity of the radius of gyration of the bolt during its change from rotary to rectilinear movement, said path being unrolled from an imaginary cylindrical surface on to a plane surface; and also the form of the path taken by a point of the bolt in actual contact with the guiding cam of the receiver when said path is unrolled from the cylindrical wall of the receiver onto a plane surface. These paths are taken through 90° of bolt rotation;

Fig. 4 is a side elevation of the working parts in the receiver as shown with the right side of the receiver cut away, the bolt being rearward at its stopped position;

Fig. 5 is a similar view with the bolt in its forward breech closed position;

Fig. 6 is another similar view but having the right side of the slide also cut away along line 6-6 of Fig. 7 to show the secondary closing spring. In this view the hammer is shown in fired position;

Fig. 7 is a transverse section through the receiver and parts contained therein along line 7-7 of Fig. 4;

Figs. 8, 9 and 10 are perspective views of the bolt, bolt carrier, and slide, respectively;

Fig. 11 is a fragmentary perspective of the bolt at its forward end and the upper side thereof at the left of the bolt lug;

Fig. 12 is a fragmentary perspective of the face of the bolt and the under side of the bolt at the right of the bolt lug;

Fig. 13 is a longitudinal section of the bolt showing the mounting of the firing pin and extractor therein;

Fig. 14 is a perspective of the buffer spring;

Fig. 15 is a perspective of the buffer spring retainer;

Fig. 16 is a perspective of the trigger;

Fig. 17 is a perspective of the sear;

Fig. 18 is a perspective of the hammer;

Fig. 19 is a perspective of the hammer spring guide;

Fig. 20 is a perspective of the hammer spring container or bridge member;

Fig. 21 is a perspective of the bolt stop;

Fig. 22 is a perspective of the bolt stop actuator;

Fig. 23 is a perspective of the follower rear supporting lever;

Fig. 24 is a perspective of the follower front supporting lever;

Fig. 25 is a perspective of the follower;

Figs. 26 and 27 are detached views of the 5 trigger, sear and hammer assembly in two successive positions to illustrate the escapement action between the sear and hammer; and

Fig. 28 is a fragmentary view in position of the follower rear supporting lever and its actuating spring.

Referring more particularly to the drawings, the metal frame or receiver 1 serves the usual purpose as a supporting container for the operative parts of the breech action and 15 firing mechanism. The receiver is adapted to be mounted in a wooden stock (not shown) and has secured to its forward end a barrel.

Bolt closing means

20 The bolt closing means preferably comprises two interslidable members or slides in collapsible relation and the closing springs therefor. Slidably mounted in the receiver is the forward slide or bolt carrier 2 having a 25 longitudinal bore 3 therethrough to receive a cylindrical bolt 4. Slidably mounted on top of the forward slide 2 (as shown in Fig. 7) is the rear slide 5. The two slides thus have a telescoping or collapsible relation with one 30 another for a reciprocatory travel in said receiver.

The rear slide 5 has a primary closing spring 6 surrounding spring guide 7 and interposed between said slide and the back 35 wall of the receiver 1. The spring 6 extends within and is adapted to be housed in the bore 8 of said rear slide. Interposed between the rear slide 5 and the forward slide or bolt carrier 2 and adapted to be housed in 40 the bore 9 of said bolt carrier is the secondary closing spring 10 surrounding a spring guide 11. The secondary closing spring 10 is purposely made slightly weaker than the primary spring 6 so that upon retraction of 45 the bolt the forward slide or bolt carrier first collapses into the rear slide and then the complete assembly moves rearward.

The bolt 4 is rotatably mounted in the bolt carrier 2 and by means on the receiver, hereinafter described, this rotation is limited to 50° of motion. A driving connection is provided between the bolt carrier and the bolt consisting of a helical cam surface 12 at the forward end of the carrier coacting with a 55 helical cam surface 13 at the rear upper side of the bolt lug 14 (see Figs. 2 and 11). The bolt lug is located at the forward end of the bolt and a bolt handle 15 is preferably formed as a continuation of said bolt lug, as shown. 60 The outer end of said bolt handle is provided with a weighted knob 16. By means of the cam surfaces 12 and 13, the rotation of the bolt from its closed position (shown in Fig. 2) to its open position (shown in Fig. 4) will 65 cam the bolt carrier 2 to the rear and con-

versely, the forward thrust of the bolt carrier by its closing spring will rotate the bolt back to its closed position. The cam surface 12 of the bolt carrier terminates in a flat portion 17 for coacting with a flat portion 18 70 on the bolt lug 14 when the bolt handle is vertical so as to provide a neutral position of rest and thus avoid any tendency toward bolt rotation while the bolt is reciprocating with the bolt carrier. Supplementing the driving connection just described is a further interlocking driving connection between the bolt and bolt carrier afforded by the helical and interfitting cam cuts 19 and 20 on the under portions respectively of the bolt and bolt carrier. These cam cuts likewise terminate in flat portions 21 and 22 to provide the rest position. When the cam cuts 19 and 20 are interengaged, no 75 rearward movement of the bolt carrier is possible without a rotation of the bolt.

Bolt locking means

The means for locking the bolt in its breech closed position are adapted to unlock the 80 bolt automatically under the force of the firing pressure. When the gun is fired, the bolt immediately starts to open, at first very slowly, almost imperceptibly, since the initial opening movement is delayed by friction and 85 inertia until after the high pressure of firing has ceased, whereupon the energy absorbed by the bolt will be sufficient to complete the opening and closing cycle. The initial period during which the force of the firing pressure is exerted against the face of the bolt and 90 thus moves the bolt backward is termed the power stroke. This period is very brief in time and the power stroke very short in extent so that no chance can occur of the cartridge bursting at the breech.

A locking cam 23, having a helical bearing surface, is provided on the right side of the receiver for coaction with a helical locking surface 24 at the rear of the bolt lug 14 (see 95 Figs. 3 and 8). On the opposite side of the bolt from the lug locking surface 24 are formed two spaced supplemental or guiding lugs 25 and 26 which have helical bearing surfaces 27 and 28 for coacting with helical counter-bearing surfaces 29 and 30 in the left hand wall of the receiver. The pitch of the coacting surfaces 27 and 29, 30 and 28, is the same as that of surfaces 23 and 24, and together said surfaces act in the nature of a 100 screw thread for imparting rotation to the bolt. The clockwise rotation of the bolt 4 is limited by the abutting of its lug 14 upon the horizontal stop shoulder 31 of the receiver right hand wall, and in this position the bolt 105 is closed against the breech.

The bolt is rotatable through 90° from this position under guidance of the helical cam surfaces, above described, and the latter part of this rotary movement is gradually directed 110

into a rectilinear movement of the bolt by means of the guiding cam 32.

The bearing surface for the locking cam 23 is of ample proportions to receive the main backward thrust of the bolt on firing, and its helical surface is preferably chosen to have an efficient angle of inclination or helix angle, as distinguished from an inefficient helix angle or one that would prevent automatic 10 unlocking by the backward thrust of the bolt. (The helix angle here considered is that defined in standard text books, namely the angle which the helical surface makes to a plane perpendicular to the axis of the helix.) The helix angle of repose, below which such helical surfaces would lock permanently against thrust, has been found by experiment to be approximately 7° 30' for lubricated surfaces, and approximately 15° 20 for dry surfaces. Anything in the close neighborhood of such helix angles for the bearing surface of a locking cam I would regard as an inefficient helix angle.

The helix angle adopted for my bearing surface 23 has been preferably chosen to be approximately twice the angle of repose for such surfaces when dry, namely about 30°, and one effect of this is to insure that the bolt will be automatically opened by the firing pressure whether the surfaces be dry or lubricated. Another effect is that a high rotative acceleration is imparted to the bolt during the power stroke so that sufficient energy will be absorbed by the bolt and moving parts to complete the opening and closing cycle of the breech action and including the automatic loading of a fresh cartridge.

A too rapid opening of the bolt during the power stroke, from such an efficient helix angle, is prevented by the moment of inertia of the rotating bolt which has been purposefully made large by a heavy bolt handle 15 projecting laterally from the bolt and having at its outer end the weighted knob 16. Both 45 the bolt handle and knob are heavier than required for their simple function as a grasping handle, and the concentration of weight in the knob 16 is for the purpose of providing as long a radius of gyration for the 50 bolt as is practicable. By this construction, the radius of gyration of the bolt is extended a considerable distance outside the receiver wall. Consequently this radius of gyration of the bolt is considerably longer than the 55 radius of the helical bearing surfaces which constitute the locking means for the bolt, viz. the main bearing surface 23 and the supplemental bearing surfaces 29 and 30.

After the termination of the power stroke, 60 the bolt continues in its helical motion for about 70° of rotation, and thereafter during the remainder of its 90° rotation is diverted into a rectilinear motion. The guiding cam 32 has a guiding surface for accomplishing 65 this change of motion in the bolt and com-

prises an initial helical portion 32a fairing into a transition curve portion 32b of somewhat elliptical form carried around to a straight line parallel with the axis of the bolt. The helical portion 32a extends for about 70° rotation of the bolt and has a helix angle about equal to that of the locking cam 23. The most favorable form of the transition curve portion 32b would be the arc of a circle, if said portion were in guiding contact with the bolt at the end of its radius of gyration; but since, as before stated, the radius of gyration of the bolt extends outside the receiver, the portion 32b has a form such as would be developed by the contacting portion of the bolt lug on the actual cylindrical wall of the receiver assuming that the extremity of its radius of gyration were guided in a circular arc in an imaginary cylinder of a radius equal to the radius of gyration of the bolt. In other words the transition curve is such that the path of contact between the bearing surface 32b and bolt lug 14 during the travel of the lug from its straight path into its helical path, corresponds to the path cut by the intersection of the radius of gyration of said bolt with the wall of the receiver when the path (as projected on a plane surface) of said bolt at the extremity of its radius of gyration is the 95 arc of a circle. In this way, the bolt is guided so that at the extremity of its radius of gyration its path is at first helical and then through the arc of a circle into a straight line and vice versa. In the diagram Fig. 100 3a, the curve *x* indicates the path of the extremity of the radius of gyration of the bolt if unrolled flat on a plane surface, and the curve *y* indicates the development of this path on the wall of the receiver 1 and 105 therefore the actual line of bearing contact between the bolt and guiding cam 32 as it would appear if unrolled on a plane surface. The straight part of *y* corresponds to the helical portion 32a and the curved part of *y* corresponds to the transition curve portion 32b.

In its opening movement, the bolt first cams back the bolt carrier 2, as previously described; and after leaving the translation curve portion 32b, the bolt lug or handle enters a slotted portion 33 of the rear slide 5, whereby it is guided in its reciprocatory movement and prevented from turning or riding off the rest position between contacts 17 and 18 (see Fig. 2). When the secondary closing spring 10 has thus been sufficiently compressed, the rear slide 5 takes up the rearward movement of the bolt and eventually 125 the bolt carrier 2 is completely collapsed into the rear slide 5 and together with the bolt the assembly travels to the rearmost position, compressing the primary closing spring 6 and fetching up against the cushion of the 130

buffer spring 34 or the rear wall of the receiver.

Buffer spring

5 The buffer spring is a heavy flat spring, doubled once upon itself like a hairpin (see Fig. 14) and is positioned in the receiver under an initial tension by means of a cam retaining lever 35 pivoted at 36 on the receiver. The lever 35 has an eccentric head 37 which cams against the lower leg of the spring to compress the same when the lever is swung from a vertical to a horizontal position in the assembly of the parts. The lever 35 is retained in its horizontal position by the pivot pin 38 of the trigger 39 which is mounted in the receiver and passes through a hole in said lever 35.

10 It will be noted that the rear upper end 34a of the spring 34 is inclined to the bottom of the bolt carrier so that the spring is compressed by the action of wedging surfaces when the bolt carrier moves to the rear. The inclination of said spring portion 34a is such as to afford a very efficient working angle 15 for the bottom of the bolt carrier in compressing the spring, and therefore a very strong tension may be provided in said buffer spring for gradually bringing said bolt carrier to a stop. On the other hand, the return force of the buffer spring acts through a very 20 inefficient working angle for imparting forward movement to the bolt carrier, and therefore will give little or no rebound thereto. In other words, the buffer spring is arranged 25 to readily absorb with a yielding opposition most of the surplus energy of the bolt carrier and then dissipate most of this energy in friction instead of returning it for the forward motion of the bolt carrier.

30 This result is attained by making the angle of inclination of the spring portion 34a to the bottom of the bolt carrier 2 only slightly above the angle of repose for said surfaces when unlubricated. Such an angle of repose 35 will be about 15° and the working angle of the spring in tending to move the bolt carrier forward, viz. the inclination of the spring portion 34a to the bottom of the bolt carrier, is 40 preferably made about 20° so as to provide a slight factor of safety in preventing any possibility of the bolt carrier sticking at the rear under the pinching action of the buffer spring.

45 *Bolt stop and follower mechanism*

The rear movement of the bolt, bolt carrier and rear slide is immediately followed by a return forward movement thereof under the 50 power of the closing springs, which forward movement of the bolt accomplishes the loading of a fresh cartridge from the magazine in the usual manner. In the event of the magazine being empty, or in other words after the 55 last cartridge from the magazine has been

fired, the return movement of the bolt is prevented by a bolt stop and the parts come to rest in the position shown in Fig. 4. The breech is thus held open and the magazine chamber may be recharged with cartridges. 70

The magazine chamber 40 is formed as an open well in the receiver and, in the embodiment shown, is adapted to be charged with cartridges from a strip type of cartridge clip. In the charging operation, the cartridge clip 75 will rest against the side shoulders 41 and 42 at the top of the magazine chamber 40, while the cartridges will be stripped therefrom in the usual manner into said chamber. The cartridges will lie in the chamber 80 in a double row stack and in staggered relation. The shoulders 41 and 42 slightly overhang the chamber space so as to properly confine the stacked cartridges therein and permit one cartridge at a time to protrude through 85 the top of the chamber, alternately from each row for being loaded by the bolt.

90 The cartridge feeding follower 43 has a stepped upper surface for engaging the bottom of the staggered rows of the cartridge stack, and is supported for a positively controlled, definitely prescribed movement in the magazine, as distinguished from the usual type of floating follower. Such a support for the follower will facilitate the charging 95 of cartridges into the magazine and also maintain the proper feeding alignment of the cartridges for loading.

99 In the embodiment shown, crossed levers support the follower. The forward lever 44 100 is pivoted at 45 on the receiver and at 46 to the rear end of the follower. The rear lever 47 is also the actuating lever and is pivoted to the receiver at 48 and to the forward end of the follower by pin 49. This forward 105 pivotal connection is also a sliding connection, for the pin 49 is slidably received in a slot 50 of the follower. The crossed portions of the levers 44 and 47 are interconnected by a pin 51 in lever 44 working in slot 52 of 110 lever 47. The actuating lever 47 is impelled by spring 53, as shown in Fig. 28.

115 Pivoted at 54 on the receiver is a bolt stop actuator 55 having a lower arm 56 adapted for engagement by the actuating lever 47 120 and an upper forked arm 57 for embracing pin 58 on the bolt stop 59. The bolt stop is pivoted to the receiver at 60 and when rocked clockwise is adapted to engage in front of the lug 25 on the bolt and hold the bolt and its 125 associated parts in the position shown in Fig. 4.

130 In the working operation of the gun with cartridges in the magazine, the follower is held depressed from the position in Fig. 4 and the lever 47 is spaced from arm 56 of the bolt stop actuator, as shown in Fig. 5. The bolt stop actuator 55 may then rock clockwise and withdraw the bolt stop 59 from the path of the bolt lug 25, and thus leave the bolt free 130

for its reciprocatory movement. Under such conditions, the bolt stop actuator will be held in its clockwise rocked position by the pressure of a finger 64 bearing on a flattened shoulder 61 of said bolt stop actuator. The finger 64 projects from the hammer spring carrier or bridge member 62 and receives force from the hammer spring later described. Of course, the effect of spring 53 is greater than 10 the pressure of finger 64 and the bolt stop will be actuated to its holding position as soon as the last cartridge leaves the magazine.

Firing mechanism

15 The hammer 63 is pivoted at 60 on the receiver (on the same pivot as the bolt stop) and is of the configuration shown in Fig. 18. 65 is the striking face of the hammer which hits the end of the firing pin 66, and side 20 wings 67 of the hammer serve as cocking abutments since they are engaged by the cocking shoulders 68 of the bolt carrier 2 for cocking the hammer when the rotation of the bolt cams the bolt carrier rearwardly as previously described. The hammer is completely cocked when the bolt completes its 90° rotation, and is held in cocked position by a sear 69 whose sear hook 70 engages the sear notch 71 on the back of the hammer. An arcuate 30 tail portion 72 is formed at one side of the hammer to ride beneath a heel portion 73 of the sear hook 70 to prevent any immediate forward movement of the sear after the hammer is released. Only when the hammer is again in cocked position will the heel portion 73 ride off the front end of the tail 72 and permit re-engagement of the sear. The sear 35 69 is pivoted on the receiver at 74 and has a rear forked portion 75 for engagement with the forward end of the trigger 39 pivoted at 38 on the receiver. At the rear of the finger portion of the trigger is a blade projection 76 adapted to normally work into a slot 77 of a safety bar 78 (see Fig. 6). It will be understood that the safety bar is mounted in the receiver for a transverse adjustable movement and that when set with its slot 77 out of register with the trigger blade 76, the trigger can not be pulled and the firing mechanism 40 will be at "Safety". A particular purpose of the hammer tail portion 72 and sear hook heel portion 73 will now be apparent, for if, after releasing the hammer, the sear could immediately rock forward again to its sear engaging position, then any misplacement of the safety bar 78 to safe position while the hammer was forward would prevent the rocking back of the sear; and if the hammer were 45 recocked, a breakage would result.

50 The hammer spring indicated at 79 serves as the impelling spring for the hammer, sear and trigger as well as restoring spring for the bolt stop in the following manner. The hammer spring is carried and partially 55 housed in a bridge member 62 (see Fig. 20)

and surrounds a spring guide or thrust rod 80 (see Fig. 19), the upper end 81 of which has a pivotal thrust bearing engaging the boss 82 of the hammer. The bridge member 62 is not pivoted or fastened to the receiver but is 70 guided therein against displacement in a floating manner. A rear projection 83 of said bridge member is slotted to straddle a guiding web 84 (see Fig. 1) of the receiver and the left side of projection 83 bears downwardly upon right leg 85 of the sear 69 to give said sear its tendency to rock clockwise and to the trigger its return movement after being pulled. As shown in Fig. 5, two humps are formed on the under side of projection 83 80 for contact with sear leg 85 to provide a double trigger pull, first soft and then hard. The forward projection or finger 64 on the bridge member rests, as before stated, on the shoulder 61 of the bolt stop actuator, and a 85 forward fin 86 on the bridge member has a guiding engagement with a slotted portion of the receiver (see Fig. 1). Thus it will be seen that the bridge member distributes the force of its hammer spring upwardly to the 90 hammer and downwardly in the manner of an equalizer bar to the sear and bolt stop actuator.

The present gun is designed for semi-automatic fire, that is the trigger must be separately pulled for each shot. An escapement is therefore provided between the trigger and sear, and the hammer to require a release of the trigger and a repulling of the same for each successive shot. The action of the escapement will be clear from Figs. 26 and 27. Below the sear notch 71 on the rear of the hammer is the escapement notch 87 adapted to be engaged by a second leg 88 of said sear (see Fig. 17).

If a continued pull is maintained on the trigger 39, the hammer, in returning to cocked position, will force its way past the end of leg 88 into the position shown in Fig. 26, wherein as long as the trigger is kept pulled 11 the leg 88 will hold the hammer cocked. As soon as the trigger pull is relieved with the parts in the position of Fig. 26, the sear will rock forward to release leg 88 from escapement notch 87 and advance sear hook 70 into 11 position to engage the sear notch 71, as shown in Fig. 27.

The firing pin 66 is mounted in an axial bore of the bolt, as shown in Fig. 13. Its rear end normally protrudes from the rear 12 of the bolt under tension of a spring 90 which also serves to actuate into forward position the ejector plunger 91. The ejector plunger consists of hollow telescoping cylinder parts containing the spring 90 and having a stop 12 lug 92 extending through a perforation 93 in the bolt wall which is wide at its rear end to permit a slight turning of the plunger 91 when retracted. As shown in Fig. 12, the plunger hole is enlarged at one side at 94 to 13

allow withdrawal of the plunger and its spring when in turned position.

The rear portion of the firing pin 66 has lateral retaining lugs 95 which bear against 5 an interior shoulder 89 of the bolt. When the firing pin is turned to register the lugs 95 with slots 96 of the bolt, the firing pin may be withdrawn from the bolt.

The shell extractor 97 is mounted for slide- 10 able movement across the rim of the bolt face and has a hooked portion for engaging the groove in the base of the cartridge C. The outer portion of the extractor has a T-way slide mounting in the front side of the bolt

15 lug 14, and the extractor is yieldingly held inward for engagement with the cartridge groove by a spring 98 acting through a tapered headed plunger 99 bearing in a cam recess 100 at the rear of the extractor. It 20 will be understood that when the extractor 97 withdraws an empty shell from the barrel, the ejector plunger 91 kicks the shell upwardly out of the receiver.

What I claim is:

25 1. In an automatic bolt action gun, in combination, a receiver, a rotary bolt therein having a projecting handle to provide a large moment of inertia for said bolt, locking means for said bolt comprising a locking lug 30 on said bolt, a locking cam in said receiver having a helical bearing surface with a helix angle of approximately 30°, the radius of gyration of said bolt and handle extending beyond said bearing surface and outside of 35 said receiver.

2. In an automatic bolt action gun, in combination, a receiver, a rotary and reciprocatory bolt therein having a projecting handle to provide a large moment of inertia for said 40 bolt, locking means for said bolt comprising a locking lug on said bolt, a locking cam in said receiver having a helical bearing surface with a helix angle of approximately 30° for contact with one side of said bolt lug and a 45 guiding surface in said receiver for contact with the other side of said bolt lug during the transition of said bolt from rotary to rectilinear movement, the radius of gyration of said bolt and handle extending beyond 50 said bearing surfaces and outside of said receiver.

3. In an automatic bolt action gun, in combination, a receiver, a bolt having a rotary and a rectilinear movement therein, a guiding 55 surface in said receiver wall for guiding the transition of said bolt from its rotary to its rectilinear movement, said guiding surface comprising a helical portion fairing into a transition curve portion which corresponds to the path cut by the intersection of the radius of gyration of said bolt with the wall of the receiver when the projected path of said bolt at the extremity of its radius of gyration is the arc of a circle.

65 4. In an automatic bolt action gun, in com-

bination, a receiver, a bolt having a rotary and a rectilinear movement therein, locking means for said bolt comprising a helical bearing surface in said receiver, said receiver also having a guiding surface in its wall for guiding the transition of said bolt from its rotary to its rectilinear movement, comprising a helical portion fairing into a transition curve portion which corresponds to the path cut by the intersection of the radius of gyration of said bolt with the wall of the receiver when the projected path of said bolt at the extremity of its radius of gyration is the arc of a circle.

5. In an automatic bolt action gun, in combination, a receiver, a bolt having a rotary movement through approximately 90° of rotation terminating in a rectilinear movement therein, said receiver wall having a guiding surface for guiding the transition of said bolt from its rotary to its rectilinear movement comprising a helical portion for guiding approximately 70° of said bolt rotation and a transition curve portion for guiding the remainder of said bolt rotation, said transition curve portion in the receiver wall corresponding to the path cut by the intersection of the radius of gyration of said bolt with the wall of the receiver when the projected path of said bolt at the extremity of its radius of gyration is the arc of a circle.

6. In an automatic bolt action gun, in combination, a receiver, a bolt having a rotary movement through approximately 90° of rotation terminating in a rectilinear movement therein, locking means for said bolt comprising a helical bearing surface in said receiver, the helix angle of which is approximately 30°, said receiver having a guiding surface in its wall for guiding the transition of said bolt from its rotary to its rectilinear movement comprising a helical portion for guiding approximately 70° of said bolt rotation and a transition curve portion for guiding the remainder of said bolt rotation, said transition curve portion in the receiver wall corresponding to the path cut by the intersection of the radius of gyration of said bolt with the wall of the receiver when the projected path of said bolt at the extremity of its radius of gyration is the arc of a circle.

7. In a gun, the combination with a breech action comprising a reciprocating member, of a single flat buffer spring arranged to readily absorb energy from the rearward movement of said member and to restore only a small part of said energy for the forward movement of said member, and retaining means for said spring comprising a cam lever for placing said spring under initial tension.

8. In a gun, the combination with a breech action comprising a reciprocating member, of a spring actuated buffer arranged to receive the blow of said rearwardly moving member through wedging surfaces, the work-

ing angle of said wedging surfaces for the return force of said buffer spring being close to the angle of repose.

9. In a gun, the combination with a breech action comprising a reciprocating member, of a spring actuated buffer arranged to receive the blow of said rearwardly moving member through wedging surfaces, the working angle of said wedging surfaces for the return force of said buffer spring being approximately 20°.

10. In a gun, the combination with a breech action comprising a reciprocating member, of a buffer comprising a flat spring having a portion extending into the path of said member at an inclination of approximately 20° to said path.

11. In a gun, the combination with a breech action comprising a reciprocating member, of a buffer comprising a flat spring having a portion extending into the path of said moving member at an inclination of approximately 20° to said path, and retaining means for said spring arranged to place said spring under initial tension.

12. In an automatic bolt action gun, in combination, a receiver, a bolt adapted to be opened by the direct application of the backward pressure of firing, closing means for said bolt comprising two slides mounted in collapsible relation in said receiver, and a separate closing spring for each slide.

13. In an automatic bolt action gun, in combination, a receiver, a bolt adapted to be opened by the direct application of the backward pressure of firing, closing means for said bolt comprising a rear slide and a forward slide mounted in collapsible relation in said receiver, a closing spring between said two slides and a closing spring between said rear slide and said receiver.

14. In an automatic bolt action gun, in combination, a receiver, a bolt adapted to be opened by the direct application of the backward pressure of firing, locking means for said bolt comprising a helical bearing surface in said receiver, closing means for said bolt comprising a rear slide and a forward slide mounted in collapsible relation in said receiver, helical driving surfaces between said bolt and forward slide, and a separate closing spring for each slide.

15. In an automatic bolt action gun, in combination, a receiver, a bolt having a rotary and reciprocatory movement therein, a handle projecting laterally from said bolt, closing means for said bolt comprising a slide mounted in said receiver and having a slotted portion to receive the handle of said bolt and prevent the rotation of said bolt during a reciprocatory movement thereof.

16. In an automatic bolt action gun, in combination, a receiver, a bolt having a rotary and reciprocatory movement therein and adapted to be opened by the direct ap-

plication of the backward pressure of firing, locking means for said bolt comprising a helical bearing surface in said receiver, and a weighted handle projecting laterally from said bolt so that its moment of inertia prevents too rapid opening of said bolt, closing means for said bolt comprising a rear slide and a forward slide mounted in collapsible relation in said receiver, said forward slide having a driving connection with said bolt, and said rear slide having a slotted portion to receive the handle of said bolt and prevent the rotation of said bolt during a reciprocatory movement thereof.

17. In an automatic bolt action gun, in combination, a receiver, a bolt having a rotary and reciprocatory movement therein and adapted to be opened by the direct application of the backward pressure of firing, locking means for said bolt comprising a helical bearing surface in said receiver and a co-acting lug at the forward end of said bolt, and a weighted handle projecting laterally as a continuation of said lug so that its moment of inertia prevents too rapid opening of said bolt.

18. In an automatic bolt action gun, in combination, a receiver, a bolt having a rotary and reciprocatory movement and adapted to be opened by the direct application of the backward pressure of firing, locking means for said bolt comprising a helical bearing surface in said receiver and a coacting lug at the forward end of said bolt, a weighted handle projecting laterally as a continuation of said lug so that its moment of inertia prevents too rapid opening of said bolt, and closing means for said bolt comprising a slide mounted in said receiver and having a slotted portion to receive the handle of said bolt and prevent the rotation of said bolt during a reciprocatory movement thereof.

19. In an automatic bolt action gun, in combination, a receiver, a bolt adapted to be opened by the direct application of the backward pressure of firing, closing means for said bolt comprising a rear slide and a forward slide mounted in collapsible relation for reciprocatory sliding movement in said receiver, a firing pin in said bolt, a hammer pivoted in said receiver and adapted to be rocked into cocked position by the rearward movement of said bolt closing means.

20. In a bolt action gun, in combination, a receiver, a bolt having a rotary and reciprocatory movement therein, a slide in said receiver, coacting cam surfaces between said bolt and slide for retracting said slide by the rotation of said bolt, a hammer pivoted in said receiver for engagement by the slide and arranged to be cocked by said retracting movement of the slide.

21. In a bolt action gun, in combination, a receiver, a bolt having a rotary and reciprocatory movement therein, a slide in said

- receiver, coacting cam surfaces between said bolt and slide for retracting said slide by the rotation of said bolt, a hammer pivoted in said receiver having a striking face and cocking ears projecting forwardly thereof, said slide having cocking shoulders for engaging said cocking ears and thereby cock said hammer upon said retracting movement of said slide.
22. In an automatic bolt action gun, in combination, a receiver, a bolt having a rotary and a reciprocatory movement therein and adapted to be opened by the direct application of the backward pressure of firing, closing means for said bolt comprising a rear slide and a forward slide mounted in collapsible relation in said receiver, closing springs for said slides, coacting cam surfaces between said bolt and said forward slide for retracting said slide by the rotation of said bolt, a hammer pivoted in said receiver for engagement by said forward slide and arranged to be cocked by said retracting movement of said slide.
23. In the firing mechanism of a gun, in combination, a bolt, a hammer, a hammer spring therefor, a sear, a bolt stop and actuator therefor, a carrier for said hammer spring positioned as an equalizer bar for distributing actuating force both to said sear and to said bolt stop actuator for the independent operation of said parts.
24. In the firing mechanism of a gun, in combination, a hammer, a sear for holding said hammer in cocked position, a trigger connected to move with the sear both in releasing and in holding the hammer, and a safety adjustable in position to prevent the movement of said trigger and sear, said hammer having a stop for engagement by said sear when released from its hammer holding position to thereby prevent a return of the trigger and sear to safety engageable position until the hammer is again cocked.
25. In the breech action of a gun in combination, a receiver, a rotary and reciprocatory bolt therein, means for locking said bolt to the breech adapted to be automatically unlocked by the firing pressure, comprising helical bearing surfaces on said bolt and receiver adapted for coacting engagement, the helix angle of said bearing surfaces being approximately twice the angle of repose for said surfaces when unlubricated.
26. In the breech action of a gun in combination, a receiver, a rotary and reciprocatory bolt therein, means for locking said bolt to the breech adapted to be automatically unlocked by the firing pressure, comprising helical bearing surfaces on said bolt and receiver adapted for coacting engagement, the helix angle of said bearing surfaces being approximately 30°.
27. In the breech action of a gun in combination, a receiver, a rotary and reciproca-
- tory bolt therein, means for locking said bolt to the breech adapted to be automatically unlocked by the firing pressure, comprising helical bearing surfaces on said bolt and receiver adapted for coacting engagement, the helix angle of said bearing surfaces being approximately twice the angle of repose for said surfaces when unlubricated, said bolt being formed with such distribution of its mass as to have a radius of gyration considerably longer than the radius of said helical bearing surfaces.
28. In the breech action of a gun in combination, a receiver, a rotary and reciprocatory bolt therein, means for locking said bolt to the breech adapted to be automatically unlocked by the firing pressure, comprising helical bearing surfaces on said bolt and receiver adapted for coacting engagement, the helix angle of said bearing surfaces being approximately twice the angle of repose for said surfaces when unlubricated, said bolt having an abnormally weighted portion projecting radially outside of said receiver so as to give said bolt a radius of gyration considerably longer than the radius of said helical bearing surfaces.
29. In the breech action of a gun in combination, a receiver, a rotary and reciprocatory bolt therein, means for locking said bolt to the breech adapted to be automatically unlocked by the firing pressure, comprising helical bearing surfaces on said bolt and receiver adapted for coacting engagement, the helix angle of said bearing surfaces being approximately twice the angle of repose for said surfaces when unlubricated, and a radially projecting handle on said bolt having an abnormally weighted outer end so as to give said bolt a radius of gyration considerably longer than the radius of said helical bearing surfaces.
- In testimony whereof I have affixed my signature.
- JOHN D. PEDERSEN.
